UNITED STATES PATENT OFFICE

AUGUST J. MOTTLAU, OF PITTSBURGH, PENNSYLVANIA, ASSIGNOR TO WESTINGHOUSE ELECTRIC & MANUFACTURING COMPANY, A CORPORATION OF PENNSYLVANIA

THERMOSTATIC REGULATOR

Application filed April 8, 1924, Serial No. 704,989. Renewed October 25, 1928.

My invention relates to temperature responsive devices and particularly to thermostatic regulators.

One object of my invention is to provide a thermostatic regulator that shall accumulate a series of internal stresses produced by small temperature changes and impress the resultant strain upon a spring in such manner that the latter moves with a snap action.

10 It is a further object of my invention to provide a thermostatic regulator that shall be particularly adapted for insertion into domestic appliances wherein the saving of space is a material consideration.

15 Another object of my invention is to provide a thermostatic regulator that shall be capable of adjustment without the addition of external details that would increase the overall dimensions thereof.

20 In the accompanying drawings,

Figure 1 is an enlarged elevational view of a thermostatic regulator embodying my invention,

Fig. 2 is a sectional view thereof taken 25 along the section line II-II of Fig. 1, and

Fig. 3 is a sectional view of a detail thereof taken along the section line III-III of Fig. 1.

My invention comprises, in general, a 30 frame 1 that yieldingly supports a pre-shaped spring 2 that controls a circuit comprising contact members 4 that are supported on the frame 1.

The frame 1 comprises a strip of U-shape 35 and composed of materials 5 and 6 having different thermal co-efficients of expansion. The material 5, which may be brass, should have a higher thermal co-efficient of expansion than the material 6, which may be invar 40 steel, and should be placed on the outer side of the frame. With this disposition of parts, when the frame 1 is subjected to increase in temperature, the upper ends of the frame 1 will be caused to move inwardly by reason of 45 the greater expansion of the strip 5 than of the strip 6.

A bracing member 7 is secured by rivets 8 or by other well known means to the central portion of the base section of the frame 1, 50 and it extends upwardly slightly beyond the

free ends of the frame 1. The up-turned end 9 of the brace 7 supports an adjusting screw 11 for a purpose to be hereinafter described.

Referring to Fig. 2, the brace 7 does not 55 extend laterally beyond the width of the frame 1. From an axis at substantially two-thirds of the length of the brace 7, projecting arms 12 and 13 extend outwardly terminating in fingers 14 and 15, between which 60 are fitted the freely moving ends of the frame member 1. An adjusting screw 16 is fitted to one of the fingers 15 for a purpose to be hereinafter described. The shape of the entire brace member 7 is substantially that of a 65 cross with the ends of the arms thereof bent at right angles to the body portion, in the same direction and for a distance not exceeding the width of the base member 1.

A block of insulating material 17 is ad- 70 justably secured by a screw 18 passing through a slot 19 therein to the brace 7. The insulating block 17 carries the contact mem- 75 bers 4 that are controlled by adjusting screws 20. The insulating block 17, the contact mem- bers 4 and the adjusting screws 20 may be re- moved from the bracing member 7, as a unit, by simply manipulating the adjusting screw 18.

The spring 2 constitutes a movable contact 80 member cooperating with the stationary con- tact members 4 and it extends between bush- 85 ings 21 inserted near the respective free ends of the frame 1. The initial shape of the spring 2 is a very important feature of the present invention. Referring to Fig. 1, the spring is bent upwardly, as at 22, for a short distance from the bushings 21, and then the spring is bent sharply downwardly to the points 23. The total distance included by 90 the curved portions 22 and 23 is small when compared with the section 24 connecting the portions 23. By reason of this configuration of the ends of the springs, initial pressure applied longitudinally of the spring 2 causes the portions 23 to move downwardly and in- 95 crease the pressure of these portions against the stationary contact members 4. This is a very important feature of the present invention for the reason that it prevents chatter- 100.

ing between the spring 2 and the stationary contact members 4 when the thermostatic regulator is very near its operating temperature.

The bushings 21 are cylindrical in form and their diameters do not exceed the width of the frame member 1. The bushings are provided with V-shaped notches 25 for the reception of the ends of the spring 2. The bushings 21 may be composed of an insulating material commonly known as "moulded lava." They are also provided with shanks 26 that extend through suitable openings in the frame 1. The shanks 26 may be circular or of rectangular cross section, as desired.

The spring 2 is provided with tail-pieces 27 that extend through openings 28 in the bushings 21 and shanks 26. The tail-pieces 27 prevent the spring 2 from being dislocated relative to the frame 1. The bushings 21 may be renewed if the thermostat becomes inaccurate by reason of the wearing away of the material thereof at their points of engagement with the spring 2.

In the operation of my thermostatic regulator, the adjustment screw 16 is so set that it bears against one of the end sections of the frame 1. I have found that a single adjustment screw 16 is sufficient to calibrate the regulator, although one may be employed at each end of the frame, if desired. The adjustment screws 20 are then set so that the stationary contact members 4 bear against the portions 23 of the spring 2 at normal operating temperature. The adjustment screw 11 is then set to provide an upper limit to the travel of the spring 2 as hereinafter described. The location of the stationary contact members 4 is roughly found by manipulation of the set screw 18 and the finer adjustments are made by means of the screws 20.

Upon an increase in temperature of the thermostatic regulator, the outer strip 5 thereof expands at a greater rate than the inner strip 6, to cause the free ends of the frame 1 to move inwardly and impress a longitudinal compressive force on the spring 2. Initial movement of the spring 2 causes the portions 23 to bear more firmly upon the stationary contact members 4 as heretofore described, while the central section 24 tends to bow upwardly. Continued longitudinal pressure on the spring 2 causes the section 24 to continue its outward movement until a state of unstable equilibrium is reached at which the entire spring 2 moves upwardly or outwardly against the screw 11 with a snap action. This snap action serves to interrupt a circuit comprising the stationary contact members 4 and the spring 2. The outward position of the spring 2 is shown in broken lines in Fig. 1.

Upon the cooling of the frame 1 to a predetermined temperature, the ends move outwardly and diminish the compression of the

spring 2, whereupon the section 24 tends to resume its initial position, as shown in full lines in Fig. 1, and the spring 2 snaps back into engagement with the stationary contact members 4. This cycle of operations may be continued indefinitely.

It will thus be seen that I have provided a thermostatic regulator that is characterized by having a frame of bimetallic material operating a pre-shaped spring for the purpose of making and breaking an electric circuit. My thermostatic regulator is also characterized by the fact that all of the operating parts are confined in a space, the width of which is approximately that of the width of the frame therefor, and that projecting adjusting features have been largely eliminated. The shape of the spring is such that a firm engagement between it and the stationary contact members is maintained until the thermostatic regulator operates to disengage the contact members. With my regulator an electric circuit may be interrupted at a predetermined temperature and reclosed at another lower predetermined temperature and the difference between these values may be adjusted to any desired value.

I do not wish to be restricted to the specific circuit connections or arrangement of parts herein set forth, as various modifications thereof may be effected without departing from the spirit and scope of my invention. I desire therefore, that only such limitations shall be imposed as are indicated in the appended claims.

I claim as my invention:

1. In combination, thermoresponsive means having a pair of supports, a stationary contact member, and a pre-shaped resilient member, comprising a main and two relatively shorter end portions having the same direction of curvature and connecting portions of sharp reverse curvature, mounted between the supports for engagement with the stationary contact member in accordance with the degree of energization of the thermoresponsive means.

2. In combination, thermoresponsive means having a pair of supports, a pair of stationary contact members, and a pre-shaped resilient member, comprising a main and two shorter end portions having the same direction of curvature and connecting portions of sharp reverse curvature, mounted between the supports, the portions of reverse curvature engaging the contact members in accordance with the degree of energization of the thermoresponsive means.

3. In combination, thermoresponsive means having a pair of supports, a pair of stationary contact members, and a pre-shaped resilient member, having a main and two shorter end portions of the same direction of curvature and connecting portions of sharp reverse curvature, mounted between the sup-

ports, the portions of reverse curvature engaging the contact members in accordance with the temperature to which it is subjected, initial longitudinal pressure on the resilient member causing the portions of reverse curvature to firmly engage the stationary contact members until the main portion buckles to thereby disengage the stationary contact members with a snap action.

4. In combination, thermoresponsive means having a pair of supports, a pair of stationary contact members, and a pre-shaped resilient member, having a main and two end portions of the same direction of curvature and connecting portions of reverse curvature, mounted between the supports, the portions of reverse curvature engaging the contact members in accordance with the degree of energization of the thermoresponsive means, initial longitudinal pressure on the resilient member causing the portions of reverse curvature to firmly engage the stationary contact members until the main portion buckles thereby disengaging the reversely curved portions from the stationary contact members with a snap action, said resilient member returning to its original position upon the reduction of the longitudinal pressure.

5. In combination, a flexible base member having a pair of supports, a pair of stationary contact members, and a pre-shaped resilient member, having a main and two shorter end portions of the same direction of curvature and connecting portions of sharp reverse curvature, mounted between the supports, the portions of reverse curvature engaging the contact members in accordance with the degree of flexure of the base member.

6. In combination, thermoresponsive means having a pair of supports, a pair of stationary contact members, and a pre-shaped resilient member having a main and two shorter end portions of the same direction of curvature and connecting portions of sharp reverse curvature, mounted between the supports, the portions of reverse curvature engaging the contact members in accordance with the degree of energization of the thermoresponsive means, initial longitudinal pressure on the resilient member causing the portions of reverse curvature to firmly engage the stationary contact members until the main portion buckles thereby disengaging the portions of reversed curvature from the stationary contact members with a snap action.

7. In combination, thermoresponsive means, cooperating supporting means, a pair of stationary contact members, and a pre-shaped resilient member having a main portion, two end portions of the same direction of curvature and connecting portions of reverse curvature mounted between the supports, the portions of reverse curvature engaging the contact members in accordance

with the degree of energization of the thermoresponsive means, initial longitudinal pressure on the resilient member causing the portions of reverse curvature to firmly engage the stationary contact members until the main portion buckles thereby disengaging the stationary contact members with a snap action, said resilient member returning to its original position upon the reduction of the longitudinal pressure.

8. In a switch structure, a stationary contact member, a resilient member having portions of the same direction of curvature and a connecting portion of reversed curvature, the portion of reverse curvature engaging the stationary contact member, and means for imparting a longitudinal thrust to the resilient member whereby engagement between the stationary contact member and the portion of reverse curvature is maintained until one of the curved portions buckles in a direction opposite to the stationary contact member with an accompanying abrupt disengagement between the stationary contact member and the portion of sharp curvature.

9. A thermal switch comprising a stationary contact member, a single return-bent bimetallic member, and a resilient member longitudinally disposed between the ends thereof, said resilient member being of substantially sinuous shape and adapted to deflect laterally between its ends with a snap motion when subjected to a longitudinal pressure and to retrace said deflection upon the removal of said pressure, said bimetallic member being adapted to exert a longitudinal pressure on the resilient member in accordance with the temperature to which it is subjected.

10. A thermal switch comprising a return-bent bimetallic member, and a resilient member, having an end portion thereof deformed laterally of its length, disposed between the ends of the bimetallic member, said resilient member being adapted to deflect laterally of its length with a snap motion when subjected to a longitudinal pressure by the bimetallic member and to retrace said deflection upon the removal of said pressure.

11. A thermal switch comprising a return-bent bimetallic member, and a resilient member supported between the ends thereof, said resilient member having its end portions deformed laterally of its length and being adapted, when subject to a longitudinal pressure by the bimetallic member, to deflect laterally between its ends with a snap motion and to automatically retrace said deflection with a snap motion upon the removal of said pressure.

12. In combination, a bimetallic frame of substantially U-shape, a pre-shaped resilient member supported by and between the ends of the frame, a bracing member supported by the frame at its intermediate portion, said

bracing member embodying stop members for limiting the movement of the ends of the bimetallic frame, and contact members supported by said bracing member and cooperating with the pre-shaped resilient member.

5 In testimony whereof, I have hereunto subscribed my name this 28th day of March, 1924.

AUGUST J. MOTTLAU.
